THE NORRIS PETERS CO., PHOTO-LITHO., WASHINGTON, D. C.

UNITED STATES PATENT OFFICE.

FRANCIS C. W. STELTER, OF NEW YORK, N. Y.

MERCERIZING-MACHINE.

SPECIFICATION forming part of Letters Patent No. 650,442, dated May 29, 1900.

Application filed August 25, 1899. Serial No. 728,516. (No model.)

To all whom it may concern:

Be it known that I, FRANCIS C. W. STELTER, a citizen of the United States, residing at New York, (Astoria, Long Island,) State of New York, have invented certain new and useful Improvements in Mercerizing-Machines, of which the following is a specification.

My invention relates to that class of apparatus used for supporting and handling hanks or skeins of yarn during the dyeing or mercerizing process, and has for its object the construction of such a machine that will permit easy and ready handling of the material to be dyed or mercerized, while maintaining it under suitable tension; and my invention consists of certain devices and combination of devices, as will be hereinafter more fully described.

In the drawings forming part of this specification, Figure 1 is a side elevation of a machine embodying my improvements, parts being shown in section to more clearly illustrate the connection and arrangement thereof. Fig. 2 is a plan view of the same. Fig. 3 is an enlarged detail of one end of the skein-supporting frames, showing parts in section. Fig. 4 is a view, parts being broken away, showing a modification.

Supported so as to freely turn in its upper and lower step-bearings A A' is the upright rod B, provided, preferably, at either end with conical or other suitably-formed supporting-bearings b b', seated in correspondingly-shaped recesses in the step-bearings A A', secured to any appropriate framework. In the present instance I have shown the bearings A A' secured to the floor and ceiling, respectively; but they may be attached in any usual manner to any framework, it being necessary only that they shall afford upper and lower bearing means for the upright rod B, in which said rod may freely turn.

Secured to the upright B a short distance above its lower bearing b is a plate B', and in corresponding relation near the upper end of upright B is a similar plate B². These plates revolve with the upright B and serve to support between them the frame-supports C, which are connected to said plates in any approved manner, as by the small socket-pieces c, into the openings of which the ends of the frame-supports C project and in which they

may rotate. While I have shown four of such supports C carried by the plates B' B², it is to be understood that the number of such frame-supports is not material and that there may be more or less, as desired. Each of the frame-supports C carries a sleeve C', free to move longitudinally thereof and to turn thereon, and projecting from said sleeves are the coupling-pieces c², which serve to connect the sleeves C' with their respective skein-supports D by means of the long downwardly-projecting arms d. The skein-supports consist of the rollers d' d², suitably journaled at d⁹ d¹⁰, Fig. 3, in bearing-sleeves d³ d⁴, formed on the side arms d⁵ and d⁶ of the frame. These rollers are free to turn in their bearings, and the upper roller of each pair constituting the skein-support has its outer bearing-pin extended through the side arm d⁵ and formed with an angled end d⁷ to receive a crank or other means to rotate the roller.

In order that proper tension may be given to the skein of yarn while being subjected to the dyeing or mercerizing process and to enable the skeins to be readily taken off and put on their supporting-frames, I provide the following mechanism: The skein-supporting frame is preferably formed of tubing in order to render it light and durable, and I make the side arms of the frame, preferably in two parts d⁵ and d⁶, the upper part being internally screw-threaded to receive the exterior threads on the screw-shafts d¹², connected to the lower part d⁶ of the side frames. The lower ends of the screw-shafts project into the upper open ends of lower part d⁶ of the side frames and have fixedly secured thereto the bevel-gears d¹⁴. Passing through the lower parts d⁶ of the side frames, which are suitably perforated to receive it, is the shaft d¹⁵, which carries bevel-gears d¹⁶, intermeshing with the corresponding bevel-gears d¹⁴, secured to the screw-shafts d¹². A yoke d¹⁷ on either side of the frame embraces at one end the shaft d¹⁵ and is bent to loosely embrace by its other end the screw-shafts d¹² above the bevel-gears d¹⁴, as will appear from Fig. 3. Immediately above this end of the yoke d¹⁷ a washer d¹⁸ is secured to the screw-shaft by set-screw d¹⁹. Thus it will be seen that while the screw-shaft can be freely rotated through the bevel-gear connection de-

scribed the screw-shafts d^{12} maintain a fixed relation to the lower parts d^6 of the skein-supports, and as they screw into or out of the upper side pieces d^5 they carry the side pieces d^6 , and consequently the lower roller d^2 , secured thereto, toward and from the upper roller d^1 . The end of shaft d^{15} is preferably provided with a squared or angled end d^{20} , on which a crank may be placed to turn the bevel-gears, and consequently the screw-shafts, in unison, and thereby move the roller d^2 toward and from the upper roller. In order to stiffen the skein-supporting frames, I provide a cross-rod d^8 to connect them near the upper ends, and to the shaft d^{15} I secure washers $d^{21} d^{22}$ on opposite sides of the end of the yoke d^{17} .

The frame-supports C are made hollow, being preferably formed of tubing in which is guided the counterbalance-weights L , which are connected to the skein-supports D by means of cords or chains l , which pass over guides l' in the upper part of the supports and are connected to the skein-supports D by the eye-bolts c' . Thus at all times the skein-supports are counterbalanced and can be readily moved by hand up or down on the frame-supports C .

In Fig. 4 I have shown a slight modification wherein only one frame-support C is used, and in this case such frame-support is held to turn in suitable bearings $s s$ and carries, by the sliding sleeve C' , two skein-supports D , which are of the same construction as those above described and are counterbalanced by the sliding weight L , which is connected to said frame-supports by the cords or chains $s' s'$. As in the construction before described, the frame-support C is made of tubing to contain the sliding weight L ; but in this form of construction I preferably, though not necessarily, connect both frames to the same weight. By making the frame-supports hollow the weights are conveniently inclosed to be out of the way.

Situated around the upright rod B and its frame-supports are a suitable number of tanks or vats 1 2 3 4, preferably corresponding in number to the frame-supports. These tanks or vats are adapted to contain the dye-baths, or in case the apparatus is to be used for mercerizing one tank or vat will contain the chemical bath and the next the neutralizing bath, and so on alternately around the entire series of vats, so that as one skein-support and its load of fibrous yarn is being treated to one bath the next is in position to be lowered into the adjoining vat, and after treatment therein can be raised, the skein removed, a new one substituted, and the entire series of frame-supports turned to the next vat, thus bringing the skein-supports successively over the appropriate vats for treatment or removal.

The operation of the device is as follows: Assuming the skein-supports to be in raised position, (shown to the left of Fig. 1,) the shaft d^{15} is revolved by a suitable crank to cause

the lower roller d^2 to approach the upper roller slightly, whereupon a load of yarn in the form of a skein or hank is slipped over the ends of both rollers and the motion of the crank reversed to separate the rollers and put the yarn under tension. The skein-supports are then lowered into the appropriate vats by slight hand-pressure, and in order that all portions of the skein shall be treated the crank is applied to the projecting end d^7 of the upper roller and turned to cause the skein to travel around and between both rollers. The peculiar connection of the skein-supporting frames D to the sleeves C' , by means of the parts $c^2 c^2$ and the long down-projecting arm d , permits the skein-supports to be lowered well into the vats. When the skeins have received full treatment in their respective vats, they are raised therefrom by a slight upward pull, the counterbalancing-weight necessitating only a slight expenditure of force, and then the entire series of frame-supports C and upright B are turned to bring the skein-supports above the next adjacent vats, into which they are lowered, as before, and the operation of turning the upper rollers is repeated. It will thus be seen that while the device is of very simple construction it has a very large capacity and is easily operated.

Having thus described my invention, what I claim, and desire to secure by Letters Patent, is—

1. In a machine for dyeing or mercerizing, the combination of a central revoluble upright, plates connected to the upper and lower ends of said upright, a plurality of vertical frame-supports connected at their upper and lower ends to said plates, skein-supporting frames slidingly supported on said frame-supports, and counterbalance-weights connected to said frames.

2. In a machine for dyeing or mercerizing, the combination of a hollow frame-support, a counterbalance-weight movable in and guided by said support, a sleeve mounted to have sliding movement on said frame-support, a skein-supporting frame depending from said sleeve and offset therefrom, and connections between said skein-supporting frame and the counterbalance-weight.

3. In a machine for dyeing or mercerizing, the combination of a central revoluble upright, vertical frame-supports adapted to revolve therewith, and skein-supporting frames slidingly mounted on said frame-supports.

4. In a machine for dyeing or mercerizing, the combination of a central revoluble upright, hollow frame-supports mounted to revolve therewith, skein-supports having sliding connection with said frame-supports, a counterbalance movable in each of said frame-supports, and connections between the counterbalance and the sliding skein-supports.

5. In a machine for dyeing or mercerizing, the combination of a plurality of vertical frame-supports connected together to turn

about a common axis, and skein-supporting frames slidingly mounted upon said vertical supports to have independent vertical adjustment.

5 6. In a machine for dyeing or mercerizing, the combination of a revoluble upright, frame-supports connected thereto to revolve therewith, sleeves mounted to slide on said frame-supports, skein-supporting frames offset and depending from said sleeves, and a counterbalance for each of the skein-supports.

7. In a machine for dyeing or mercerizing, a skein-support formed of tubing and comprising side arms formed of separate sections, a screw connection between said sections, a roller carried by each of said sections, and means to simultaneously operate the screw connections between the separate sections of the side arms.

20 8. The combination of a frame-support, a sleeve sliding thereon, a skein-supporting frame formed of tubing and depending from

said sleeve, and couplings to offset the skein-support from said sleeve.

9. A skein-support consisting of two side arms one of which is prolonged above the support, rollers journaled in said side arms, means to revolve one of said rollers, devices for adjusting the distance between the rollers, and a supporting-sleeve connected to the prolonged side arm.

10. The combination of a hollow revoluble frame-support, a skein-support connected to slide thereon, a counterbalance-weight movable within said frame-support, and connection between the skein-support and said counterbalance.

In testimony whereof I have signed my name to this specification in the presence of two subscribing witnesses.
